(57) **CLAIM**

The ornamental design for a taillight, as shown and described.

DESCRIPTION

FIG. 1 is a perspective view of the taillight.

FIG. 2 is an elevational view of the front end of the taillight.

FIG. 3 is a top plan view of the top plan of the taillight.

FIG. 4 is a bottom plan view of the bottom plan of the taillight.

FIG. 5 is an elevational view of the back end of the taillight.

FIG. 6 is an elevational view of the side of the taillight; and, FIG. 7 is an elevational view of the opposite side of the taillight.

The broken line portion of the Figure drawings is included to show portions of the taillight that form no part of the claimed design.

1 Claim, 7 Drawing Sheets
